UNITED STATES PATENT OFFICE.

ARNOLD SESSLER, OF NEW YORK, N. Y.

DESIGN FOR A BICYCLIST'S STOCKING.

SPECIFICATION forming part of Design No. 24,637, dated August 27, 1895.

Application filed June 14, 1895. Serial No. 552,854. Term of patent 14 years.

To all whom it may concern:

Be it known that I, ARNOLD SESSLER, a citizen of the United States, residing at New York city, in the county and State of New York, have invented and produced a certain new and original Design for a Bicyclist's Stocking, of which the following is a specification, reference being had to the accompanying drawing, forming a part thereof.

My invention relates to designs for stockings, which will closely resemble leggins, such as are commonly used by bicyclists.

The leading feature of my design consists of a stocking provided on one side with a substantially vertical row of buttons and with the representation of a closed buttonhole in line with each button, whereby the stocking will closely resemble a leggin or similar article.

A stocking embodying my design is shown

in the accompanying drawing, which is a side view, and wherein—

A is a stocking.

B represents a seam in the stocking, which closely resembles a separate flap.

D represents buttons sewed to the stocking in substantially a vertical line, and C represents a blind buttonhole in line with each button, and which closely resembles a closed buttonhole.

What I claim is—

The design for a stocking herein shown and described.

This specification signed and witnessed this 11th day of June, 1895.

ARNOLD SESSLER.
